UNITED STATES PATENT OFFICE.

SAMUEL W. PAGE, OF JERSEY CITY, NEW JERSEY.

FASTENING-BAND FOR PACKAGES OF MERCHANDISE.

SPECIFICATION forming part of Letters Patent No. 329,205, dated October 27, 1885.
Application filed November 28, 1882. Serial No. 77,970. (No model.)

To all whom it may concern:

Be it known that I, SAMUEL W. PAGE, a citizen of the United States, residing at Jersey City, in the county of Hudson and State of New Jersey, have invented a new and useful Improvement in Fastening-Bands for Packages of Merchandise, of which the following is a description.

The object of my invention is to provide a means for holding loose articles of merchandise together—such as kid gloves, &c. Heretofore a paper band and a pin have been used for this purpose; but the pin is liable to do damage to the delicate goods.

My improvement comprises a thin flat metal clip of special construction, and a band of paper or flexible material having said clip attached to it, for use in place of the pinned paper band heretofore used for the purpose specified. The metal clip has as constituent or integral parts of it clinching-prongs at or near its one end, and short hook-shaped catching-prongs or sharp teeth at or near its opposite end, the first-named set of prongs, serving to clinch or attach the clip to the one end or edge portion of the band, and the other catching-prongs or teeth in or near the opposite end of the clip, which projects beyond the edge of the band the clip is attached to, serving to temporarily engage with the other or opposite and plain end or portion of the band without special perforations or fastenings in said plain portion of the band to effect the engagement, and so that when the band is passed around the gloves or other articles of merchandise, and the end bearing the toothed clip is lapped over the other end the hook-shaped catching-prongs or teeth will enter the paper or material of the other end portion of the band, and hold the band fast and tight against the expansive action of the article or articles within it without injury to the goods, and providing for a ready opening of the band when required.

Figure 1 is an enlarged view of the metal clip before being applied to the band. Fig. 2 is an enlarged edge view showing the prongs as bent in applying it to the band. Fig. 3 is an edge view of the band, showing the clip securing the ends of the same; and Fig. 4 is a view of one of the ends of the band to which the clip is permanently applied.

C represents the thin sheet-metal clip having prongs B B B, that pass through and fasten the metal clip to the end of the paper band D, (see Fig. 4,) and which clip has two other prongs, A A, that project beyond the end of the paper band, and are bent inwardly to a hook shape for engagement with the other end of the band at the will of the salesman. There may be any number of these clinching-prongs 60 B and hook - shaped small sharp teeth A, which may be produced by punching or cutting and bending. The first-named ones, B, are what have hereinbefore been termed the "clinching-prongs," and the other, or short 65 hook-shaped ones, A, on the inner or under side of the projecting or overlapping end of the clip, are what have been specified as the "catching-prongs" or "teeth." The band is made plain on its end or portion in which 70 these small sharp teeth A hook or engage—that is, without any special perforations or fastening devices for said prongs or teeth to enter, the engagement being made direct with the material of the band at any point or place 75 thereon that they come in contact with when the band is closed about the goods, thus providing for the banding of different thicknesses of packages without injury to the goods, and providing for the ready opening of the band 80 when required.

I do not claim, broadly, a metal clip or fastening for connecting the ends of a flexible band, as this is not new; but

What I claim as new is—

As a new article of manufacture, a flexible band for holding articles of merchandise, as described, having its one end portion plain and without special fastening-perforations or devices, and its other end having an attached 90 metal clip arranged to project beyond said end of the band, and provided at its attached end with clinching-prongs for securing it to the band, and at its projecting or overlapping end or portion with short hook-shaped sharp 95 teeth for engagement with the plain end or portion of the band, substantially as specified.

SAMUEL W. PAGE.
